CLAIM

The ornamental design for a pogo stick, as shown and described.

DESCRIPTION

FIG. 1 is a bottom perspective view of a pogo stick of my new design. The hatched spots shown are representative of lighted areas, wherein the color of the light within each area is indicated by the particular hatching with vertical hatching indicating the color red and horizontal hatching indicating the color blue;

FIG. 2 is a top perspective view of the pogo stick of FIG. 1; and,

FIG. 3 is a front view of the pogo stick of FIG. 1.

The portions of a pogo stick shown in broken lines in FIGS. 1–3, including handle bars and a coupling therefor, a central cylinder, foot supports and a coupling therefor, a lower slider shaft, and a lower bounce element, denote the environmental use of the claimed design, are for illustrative purposes only, and form no part of the claimed design.

The broken lines defining the boundaries of the lighted areas form no part of the claimed design.
